UNITED STATES PATENT OFFICE.

FRANK D. PEARNE, OF CHICAGO, ILLINOIS, ASSIGNOR OF ONE-HALF TO JAMES E. MARTINE, OF CHICAGO, ILLINOIS.

PRINTING-TELEGRAPH SENDING APPARATUS.

1,137,894.

Specification of Letters Patent.

Patented May 4, 1915.

Application filed March 22, 1909. Serial No. 484,882.

To all whom it may concern:

Be it known that I, FRANK D. PEARNE, a citizen of the United States, residing at Chicago, county of Cook, State of Illinois, 5 have made a certain new and useful Invention in Printing-Telegraph Sending Apparatus, of which the following is a specification.

This invention relates to printing telegraph apparatus, and particularly to the sending part of such apparatus.

The object of the invention is to provide means whereby it is not necessary for a depressed key of the key-board to return to 10 normal or raised position before a second key may be depressed, thereby greatly increasing the rapidity of operation of the sending apparatus.

A further object is the provision of means 15 whereby an objectionable circuit derangement of the mechanism is prevented when one or more keys are simultaneously depressed.

A further object is to simplify and improve the construction of sending apparatus 20 employed in connection with printing telegraph apparatus, and to render the same more efficient and expeditious in operation.

Other objects of the invention will appear more fully hereinafter.

The invention consists substantially in the construction, combination, location and relative arrangement of parts, all as will be 25 more fully hereinafter set forth, as shown in the accompanying drawings, and finally 30 pointed out in the appended claims.

Referring to the accompanying drawings, and to the various views and reference signs appearing thereon, Figure 1 is a view showing the release sleeve shifted into position to release the contact operating devices. Fig. 2 is a view showing the sleeve released but the key remaining in depressed position. Fig. 3 is a view similar to Fig. 2, showing 40 means for operating the release sleeve actuating and stop cams. Fig. 4 is a view in diagrammatic section showing how the simultaneous depression of two or more keys will result in no derangement but only one 45 of keys will be effective. Fig. 5 is a view partly broken out, and partly in section, showing the relation of the stop cams and the key levers and sleeves.

The same part is designated by the same

reference sign wherever it occurs throughout 55 the several views.

In my prior application Serial No. 391,020, filed Sept. 3, 1907, I have shown, described and claimed a printing telegraph sending apparatus wherein a series of electrical impulses of differing characteristics are sent over the line wire in quick succession at each depression of a key, such apparatus including, generally, a key board, a distributor, and a sender, the key board being so organized and arranged that when any one of the keys is depressed it closes a circuit through a co-operating group of relays employed in connection with the distributor part of the apparatus. These relays select the particular group or combination of impulses corresponding to the particular key of the key-board which has been depressed, and connect the circuits of said selected group or combination of impulses to the proper and 70 corresponding contacts of the sender apparatus through which the proper line connections are made. The sender includes an automatically operated contact making drum arranged, at each cycle of operation, to make 75 one half of a revolution.

The present invention relates particularly to printing telegraph apparatus of the nature and character set forth and claimed in my said prior application for patent, and is 85 designed to render the sending apparatus thereof more efficient, reliable and speedy.

In the arrangement shown in my prior application, referred to, it is impossible to connect to the line wire the circuit terminals 90 of a group of relays corresponding to a letter and controlled by depressing a key of the keyboard, until a previously depressed key is released and returns to its normal position. That is, it is impossible to send a 95 group of impulses corresponding to any particular letter to the line wire, until a previously depressed key is released and returns to its raised position, because current continues to flow through the magnet which 100 controls the sending drum until a depressed key returns to its normal position, thereby retaining the escapement mechanism for the drum in obstructing position. The result is that the speed of operation of the apparatus 105 is very much curtailed, and, moreover, the operator must learn from the operation of the machine the length of time it is neces-

sary to hold the key depressed to enable its complete function to be accomplished before being released.

It is among the special purposes of the present invention to avoid these and other objections, and to provide means whereby one or more keys may be depressed before a previously depressed key is released, and still enable each key to properly perform its function, thereby enabling the speed of operation to be vastly increased, and at the same time relieving the operator of the necessity of determining from experience the length of time it is necessary to hold a key in depressed position to enable it to perform its proper function.

In carrying out my invention I propose to employ means which are operated by the depression of a key to complete the necessary circuits of the corresponding group of relays, as in my prior application, and to inaugurate or control the operation of the sender, whereby the proper line circuits connections are completed, and to bring into operation, by the actuation of the sender, means for releasing the key controlled contact mechanism without regard to the return of the depressed key to elevated or raised position. I also propose to employ means whereby when two or more keys are simultaneously depressed only one of them will be effective for the accomplishment of its function, thereby avoiding circuit derangements which might otherwise be caused. I also propose to employ means whereby the depression of the key is prevented before a previously depressed key has accomplished its work although the return of the previously depressed key to normal or raised position is not a necessary condition to the proper performance of the function of a subsequently depressed key. These various results may be accomplished in a wide variety of different ways and by a wide variety of specifically different mechanisms.

While, therefore, I have shown, and will now describe, one construction and arrangement of mechanism for accomplishing my desired objects, my invention, as defined in the claims, is not to be limited or restricted to the exact details shown.

In the drawing reference sign 10, designates the keys of the key board of a printing telegraph sending apparatus, and 11, the key lever. These parts may be of any suitable or convenient construction and arrangement, similar, for instance, to the key-board of a typewriter, the key levers 11, being supported for pivotal or other movement on a stud 12, mounted in the frame 13, of the machine, and normally maintained raised in any suitable manner, as for instance, by means of a spring 14, in the usual or well known manner. Each key and lever

controls the circuit connections between a corresponding pair of contact strips 15, 16. This may be effected by means of a plunger 17, arranged to be depressed by depressing its coöperating key-lever, and operating, when depressed, to cause contact strip 15, to break contact with a strip 18, and to make contact with the strip 16. These contacts control the circuits of the corresponding groups of relays which send out to line the group of impulses to produce the corresponding letter at the distant receiving station.

Instead of the key-levers directly engaging the plungers 17, when the former are depressed, I mount on each lever a sliding sleeve 19, carrying a lug or projection 20, designed, when occupying proper relative position, to engage the coöperating plunger 17, when the key is depressed, thereby operating said plunger and closing the circuit between the contact strips 15, 16. The sleeves 19 are mounted for longitudinal movement along the key levers, and are held in normal retracted position against stop pins 21, on the levers, by means of a retracting spring 32, and when in this position the lugs or projections 20, are in proper relation to bear upon their respective plungers 17, when the levers are depressed. Each sleeve 19, is provided with a lateral pin 22, with which coöperates a cam, arm or projection 23. These cam arms or projections are carried by a rock shaft 24, suitably journaled in the frame work, and operated automatically in any suitable or convenient manner, preferably in cycle with the operation of each lever. To this end, and in one form of apparatus for accomplishing the desired result within the contemplation of my invention, I pivotally mount a lever 28, upon a convenient part of the frame work, and arrange one end thereof to bear against a cam 25 carried by the drum 26, which is given a half revolution at each depression of a lever to effect the proper line connections of the relay group circuit terminals. The other end of lever 28 is connected by means of a link 27, with an arm 29, carried by shaft 24. The cam 25, is double so that the shaft 24 is given a rocking oscillation at each half revolution of the sender drum 26. A spring 30, may serve to maintain the end of lever 28, in engagement with the cam 25.

If desired, the automatic releasing sleeves 19, and their coöperating cam projections 23, may all be thrown out of action at will. This may be accomplished by hinging or otherwise suitably connecting the upper part 31, of lever 29, to the lower part thereof as indicated at 50, Fig. 3, whereby, by rocking or swinging said part 31, out of engaging relation with respect to the cam 25, the shifting movements of the releasing sleeves are no longer effected.

As above stated each contact controlling

plunger 17, when in raised position permits strips 15 and 18 to come into contacting relation, and when in depressed position circuit is broken between these strips and is completed between strips 15 and 16. All the contact strips 18 are in series with each other and with the strips 15, when all of the apparatus is in normal position, so that when any one of the plungers is depressed 5 the circuit through the strips 15, of all of the other plungers is broken, and if two or more plungers are depressed simultaneously or in very close sequence of operation only that one becomes effective for the performance of its intended function which happens 10 to be the first in the series or sequence of operation.

Having now set forth the mechanical construction of one form of embodiment of 20 my invention I will now describe the operation thereof. Assuming that all parts are in normal positions ready for operation each key and its associated lever, releasing sleeve and other parts concerned in its operation 25 will occupy the respective positions shown in Fig. 3. Now suppose the key is depressed. The first effect is that projection 20, engages the plunger 17, and depresses the latter, thereby breaking circuit connection between 30 strips 15 and 18, and completing circuit connections between strips 15 and 16. The completion of the circuit connection between strips 15 and 16, closes the circuits of the group of relays of the distributor which corresponds to the particular key that has been 35 depressed, as, for instance, from the battery B, Fig. 4, wire a, the particular pair of strips 15, 16, which have been closed upon each other, thence through wire b, c, d, etc., 40 as the case may be, to and through the corresponding group of relays of the distributor D, and return wire f, to battery B. The closing of this circuit effects the proper selection of impulses to be sent to line and 45 also inaugurates the action of the mechanism which controls the operation of drum 26, through which the proper line connections are made, said drum being caused by such mechanism to make one half of a revolution, 50 all as more fully shown and explained in my prior application above mentioned. This half revolution of the drum 26, causes the cam 25, to impart one complete oscillation of lever 28, thereby, on its movement in one 55 direction, rocking the shaft 24, so as to advance the cam arms or projections 23, into position underneath the pins 22, to form stops to prevent the depression of any other key lever until the cam arms or projections 60 are returned out of the path of movement of said pins when the key levers are depressed. At the same time the front edge of the cam arm or projection 23, which operates with the particular key lever which 65 has been depressed to inaugurate the oper-

ation, engages the pin or projection 22 on said lever, as shown in Fig 1, and thereby shifts or moves the sleeves 19, lengthwise upon the key lever until the projection 20 of said sleeve clears the contact operating 70 plunger and leaves such plunger free to rise, thereby breaking the circuit connection between strips 15 and 16, and restoring connection between strips 15 and 18, and hence restoring the apparatus to condition to enable any other key lever to be depressed and to perform its function when depressed, without awaiting the return of the previously depressed key lever to its raised position. 75

It will be observed that all of the foregoing operations take place during a portion only of the half revolution of the drum 26. In other words, when any particular key is depressed to inaugurate the cycle of operations necessary to transmit a letter, the circuit connections controlled by such key lever are automatically released as soon as the key lever has properly performed its function, and then one or more other key levers, 80 may be manipulated without awaiting the return of the first key to be depressed to its raised position. The continued movement of the drum 26, to complete its half revolution causes the cam 25, to operate the lever 95 28, in the opposite direction thereby returning the cam arms or projections 23, out of stop relation with respect to the pins 22 on the sleeve of those key levers which have not been depressed, leaving them free to be 100 operated and at the same time releasing the pin 22, of the sleeve of the lever which was depressed, and hence permitting the retracting spring 32, to draw said sleeve back toward initial position. This sleeve, however, 105 will be prevented from attaining its final normal position until the key lever is released and rises, because the projection 20, will bring up against the plunger 17, as shown in Fig. 2 until the key lever returns 110 to its raised position. As soon as the key lever returns to its raised position however, the parts associated therewith are restored to normal position, ready for the next operation. Should two or more key levers be 115 depressed at the same time both pins 22 will clear their associated cam arms or projections 23 but only one key, the key between the battery and the other depressed key or keys, will be effective since, as is 120 seen in Fig. 8, the circuit of the strips 15, is broken when the strip between the battery and other depressed key or keys is moved out of contact with its associated strip 18, thereby doing away with all circuit derangement. If, however, two or more keys should not be depressed at the same time, even if almost the same time, only on the first key depressed will the pin 22 clear 125 its associated cam arm or projection 23, 130

and therefore only the first key will complete the circuit and be effective.

From the foregoing description it will be seen that I provide a construction of sending mechanism for printing telegraph apparatus which is simple and efficient, automatic in operation when once inaugurated, and wherein a very high speed of transmission can be secured. It will also be seen that the operator is required merely to manipulate the keys and is not dependent upon his discretion or experience to determine the length of time he must hold a key in depressed position in order to be sure that it has completely performed its proper function. It will also be seen that the return of a key or its lever to raised position is not necessary before a second key or other keys can be manipulated.

Having now set forth the object and nature of my invention, and a construction embodying the principles thereof, and having described such construction, its purpose, function and mode of operation thereof, what I claim as new and useful and of my own invention, and desire to secure by Letters Patent is:—

1. In a printing telegraph sending apparatus, the combination with keys, sleeves mounted thereon and circuits controlled thereby, of means operating a sleeve for restoring the circuits to normal condition after manipulation of a key, without regard to the restoration of the key to normal position.

2. In a printing telegraph sending apparatus, the combination with keys, sleeves mounted thereon and circuits controlled thereby, of automatic means operating a sleeve for restoring the circuits to normal condition after manipulation of a key, without regard to the restoration of the key to normal position.

3. In a printing telegraph sending apparatus, a key, contacts arranged to be closed by the movement of the key, and means carried by the key but operating independently of the key movement for opening said contacts.

4. In a printing telegraph sending apparatus, circuit contacts, means for controlling said contacts, a key for actuating said controlling means to close said contacts, and devices carried by but operable independently of the key, while the latter is depressed, for releasing said controlling means to open said contacts.

5. In a printing telegraph sending apparatus, circuit contacts, a key for closing said contacts, and means mounted on but operating independently of the key for opening said contacts.

6. In a printing telegraph sending apparatus, a series of keys, circuit contacts con-

trolled thereby, plungers operated by the keys for closing the contacts controlled thereby, and means independent of the key for releasing said plungers.

7. In a printing telegraph sending apparatus, a key, a sleeve mounted on said key, means operated by the sleeve when the key is depressed for closing circuit contacts, and means for moving the sleeve on the key to release the contacts without regard to the key movement.

8. In a printing telegraph sending apparatus, a key, a sleeve movably mounted, circuit contacts arranged to be closed by said sleeve when the key is depressed and means for automatically shifting the sleeve to release the contacts.

9. In a printing telegraph sending apparatus, a key, a sleeve movably mounted thereon, circuit contacts arranged to be operated by said sleeve when the key is depressed, means for normally maintaining said sleeve in operative relation with respect to the contacts, and means for shifting said sleeve on the key when in depressed relation to release the contacts.

10. In a printing telegraph sending apparatus, a series of keys, studs carried thereby, circuits controlled by said keys, and means made operative when any key is depressed for engaging the studs on the remaining keys to prevent the depression thereof.

11. In a printing telegraph sending apparatus, a series of keys, studs carried thereby, circuits controlled by said keys, means made operative when any key is depressed for engaging the studs on the remaining keys to prevent the depression thereof, and means independent of the movement of the depressed key for releasing said stop means.

12. In a printing telegraph sending apparatus, a series of keys, studs carried thereby, circuits controlled by said keys, a series of cam arms coöperating with said studs, and means for operating said cam arms.

13. In a printing telegraph sending apparatus, a series of keys, circuits arranged to be closed by said keys when depressed a corresponding series of cam arms, and means actuated by a cam arm, when its associated key is depressed to close a circuit, for opening said circuit.

14. In a printing telegraph sending apparatus, a series of keys, a sleeve movably mounted on each key, circuit contacts closed by said sleeves when their carrying keys are depressed, and cam arms operating to engage the sleeve on a depressed key to shift the same thereby opening said contacts.

15. In a printing telegraph sending apparatus, a series of keys, a sleeve movably mounted on each key, a stud carried by each sleeve, a cam arm operating to engage its associated cam arm or projection,

depressed to move the sleeve on said key, means for operating said cam arms, and circuit contacts controlled by said sleeves.

16. In a printing telegraph sending apparatus, a series of keys, a sleeve movably mounted on each key, a stud carried by each sleeve, a cam arm arranged to coöperate with each stud, means for moving said cam arms in unison, and circuit contacts controlled by each sleeve.

17. In a printing telegraph sending apparatus, a series of keys, a sleeve movably mounted on each key, and carrying a stud, a cam arm coöperating with each stud, and normally held out of coöperative relation with respect to the studs, means made operative when any key is depressed for moving all of said cam arms into operative position with respect to the studs, and circuit contacts controlled by said sleeves.

18. In a printing telegraph sending apparatus, a series of keys, a sleeve movably mounted on each key and carrying a stud, a cam arm normally held out of the path of said stud, means made operative when a key is depressed for moving the corresponding cam arm into position to engage the stud on the sleeve of the depressed key, and circuit contacts controlled by said sleeve.

19. In a printing telegraph sending apparatus, a series of keys, circuits controlled thereby, stop devices associated with said keys, and operating to release the circuit controlling means when a key is depressed irrespective of the movement of the key,

means for actuating said stop devices, and means for rendering said stop devices inoperative at will.

20. In a printing telegraph sending apparatus, a series of keys, circuits controlled thereby, automatic release mechanism for said circuits including a rocking lever having a hinged section, means for rocking said lever and means for throwing the hinged section of said lever out of position for use at will.

21. In a printing telegraph sending apparatus, a series of keys, circuits controlled thereby, stop devices for said keys, a lever mechanism for operating said stop devices and a cam for actuating said lever devices.

22. In a printing telegraph sending apparatus, a series of keys, sleeves movably mounted on said keys and carrying studs, circuit contact devices controlled by said sleeves, cam arms coöperating with said studs and normally held in inoperative relation with respect thereto, a rock shaft on which said cam arms are mounted, a rocking lever connected to rock said shaft, and a rotatable cam for rocking said lever.

In testimony whereof I have hereunto set my hand in the presence of the subscribing witnesses, on this 15th day of March A. D., 1909.

FRANK D. PEARNE.
